SAFETY PIN

Isadore Glasband, Hartford, Conn.

Application June 15, 1950, Serial No. 10,546

Term of patent 14 years

(Cl. D86—10)

To all whom it may concern:

Be it known that I, Isadore Glasband, a citizen of the United States, residing at Hartford, in the county of Hartford and State of Connecticut, have invented a new, original, and ornamental Design for a Safety Pin, of which the following is a specification, reference being had to the accompanying drawing, forming part thereof.

Fig. 1 is a top plan view of a safety pin embodying my new design, the conventional body portion being illustrated in broken lines.

Fig. 2 is a side elevational view of the safety pin, the opposite side being substantially the same in appearance as the side shown.

Fig. 3 is an end elevational view of the safety pin.

My design for a safety pin is characterized by the particular ornamentation on the head thereof comprised of swirls radiating from a floral element located on the top of the head in association with the sun burst elements located on the end of the head and adjacent the tips of the keeper ears.

I claim:

The ornamental design for a safety pin, substantially as shown, and described.

ISADORE GLASBAND.
